COMBINED DENTAL FLOSS STRIP AND MOLDED PICK END

Richard L. Wells, 4503 N. 32nd St.,
Phoenix, Ariz. 85018

Filed July 14, 1972, Ser. No. 271,774

Term of patent 14 years

Int. Cl. D24—99
U.S. Cl. D24—1

FIG. 1 is a perspective view of a combined dental floss strip and molded pick end showing my new design;

FIG. 2 is a perspective view as seen from the right of FIG. 1; and

FIG. 3 is a cross-sectional view taken on the line 3—3 of FIG. 2.

I claim:

The ornamental design for a combined dental floss strip and molded pick end, as shown and described.
